UNITED STATES PATENT OFFICE.

GERARD SWOPE, OF NEW BRUNSWICK, NEW JERSEY, ASSIGNOR TO WESTERN ELECTRIC COMPANY, OF NEW YORK, N. Y., A CORPORATION OF ILLINOIS.

TELEPHONE SWITCHING APPARATUS.

1,086,869.

Specification of Letters Patent.

Patented Feb. 10, 1914.

Application filed April 14, 1911. Serial No. 620,984.

To all whom it may concern:

Be it known that I, GERARD SWOPE, citizen of the United States, residing at New Brunswick, in the county of Middlesex and State of New Jersey, have invented a certain new and useful Improvement in Telephone Switching Apparatus, of which the following is a full, clear, concise, and exact description.

10 This invention relates to telephone apparatus and more particularly to house telephones. Its object is to provide a simple and inexpensive terminal apparatus for telephone stations.

15 In accordance with the invention there is provided a springjack at each of several terminal stations and a plug switch, the springjacks forming the terminals of telephone lines and the plug the terminal of a portable telephone, together with means, preferably in the form of a hook, fixed upon the plug for removably supporting the telephone when not in use.

20 More particularly the invention provides 25 a springjack, together with a push button, for calling, mounted on the rear side of a flat plate which may be installed flush with the wall where a telephone is to be used; the telephone being connected to the plug by a flexible cord and comprising the ordinary hand combination set consisting of a transmitter and receiver, is thus adapted to be taken from station to station as desired for use. The plug may be inserted in any spring- 30 jack and the telephone hung on the hook fixed to the plug so as to be readily accessible for use when desired at that station. Preferably the plug is provided with two terminal rods mounted side by side in an insulating block, one of the terminals being 35 of larger size than the other, and the springjack openings being of corresponding sizes so that the circuit connections will necessarily be the same whenever and wherever 40 the plug is inserted.

45 The invention will be more fully understood by reference to the accompanying drawing, wherein—

Figure 1 is a side perspective of a plug together with a hand combination telephone set supported thereon. Fig. 2 is a plan view of the plug with the body portion in section. Fig. 3 is a front view of a plate containing a springjack and push button. Fig. 4 is a

cross sectional view on the line 4—4 of Fig. 55 8, and Fig. 5 is a rear view of the plate.

In the drawing, the hand combination telephone set 1 is provided at its upper end with a ring 2 and extending from its lower end a flexible cord 3, the set being supported 60 by placing the ring over the end of a hook 4 mounted upon the plug 5. This plug comprises besides the hook 4 and body portion 6, two contact terminal rods 7, 8, of different diameters. An extension 9 of the hook 4 65 passes through the block and is threaded at its end to engage a nut 10 which holds the hook firmly in place in the block. The terminal rods 7, 8, extend through the block from end to end as shown, and are provided 70 with holes 11 for the terminal clips 12 of the cord. The connections are made secure by set screws 13.

Referring to Figs. 3, 4 and 5, there is shown a mounting plate 14 provided with a 75 push button 15 and spring-jack sockets 16, 17, these sockets being of suitable sizes to permit entrance of the contact rods 7, 8 of the plug. On the rear edge of the plate 14 is an insulating block 18. Each socket is 80 provided with a sleeve 19 threaded into the block 18 and concentric with the openings in the plate 14, said openings being a little larger than the sockets in order that the terminal rods 7 and 8 of the plug will not 85 make contact with the plate 14 when inserted. Mounted upon the block 14 are two plates or spring clips 20, 21 held in place by bolts 22, 22, which also serve as binding posts for the line connections. The two 90 plates 20, 21 are formed at one end into a pair of contact points 23, 24, adapted to be closed by the push button 15, and at the other end into a pair of contact springs 25 which engage the rods 7, 8 when the plug is 95 inserted. The ends of these rods are grooved as shown so as to lock the plug in place by engagement with the ends of the springs 25.

In practising the invention, a house or other building may be equipped with as 100 many terminal stations as desired and at each station there will be installed one of the push button and springjack plates 14. The expense of installing a simple terminal apparatus of this kind is inconsiderable and the installation may be made with the idea of first merely using the push buttons at 105 the stations in connection with an annun-

ciator at some central point. The provision of the springjack upon the plate, in addition to the push button, provides a simple and inexpensive means for connecting a portable telephone at any future time, the push button being then used to signal the central telephone station.

I claim:

1. In a telephone substation a wall plate, 10 a pair of contact springs mounted thereon forming the terminals of a telephone line, a push button coöperating with said contact springs to close the line for signaling purposes, and a plug engaging said contact 15 springs to connect a telephone instrument across the line for talking purposes.
2. In a telephone substation a wall plate,

an insulating plate mounted thereon, both of said plates being provided with apertures passing therethrough, a pair of contact springs mounted on said insulating plate, a push button passing through one of said apertures and being adapted to bring one end of each of said contact springs into engagement with the other, the other ends of said springs coöperating with other of said apertures to form spring jacks.

In witness whereof I hereunto subscribe my name this 12th day of April, A. D. 1911.

GERARD SWOPE.
